STOP MOTION MECHANISM FOR KNITTING MACHINES

Jacob Wachsman, Brooklyn, N. Y.

Application June 22, 1950, Serial No. 169,621

8 Claims. (Cl. 66—163)

1

The present invention relates to stop motion mechanisms, and, more particularly, relates to improved stop motion mechanisms for use in connection with knitting machines and the like, which mechanisms are of the type responsive to the breakage of the yarn, thereby requiring a predetermined tension in the yarn at all times in order to prevent the stop mechanism from operating upon the appearance of slack in the yarn during normal operation of the machine.

Accordingly, an object of the present invention is to provide such stop motion mechanism having improved slack take-up means which are simple and economical in construction and reliable in operation.

Another object is to provide such stop motion mechanism particularly adapted for controlling an electrical circuit which effects stoppage of the machine.

Another object is to provide such stop motion mechanism wherein a single switch circuit is adapted to be controlled by a pair of yarn tension responsive members whereby the number of electrical circuits is greatly reduced in knitting machines wherein a multiplicity of strands of yarn control the stoppage of the machine.

A further object is to provide such stop motion mechanism wherein movement of a pair of yarn tension responsive members is resisted by springs which are adjustable by common means whereby adjustment of the stop motion mechanisms is simplified.

Other and further objects will be obvious upon an understanding of the illustrative embodiment about to be described, or will be indicated in the appended claims, and various advantages not referred to herein will occur to one skilled in the art upon employment of the invention in practice.

In accordance with the invention, the foregoing objects and advantages are accomplished by providing a stop motion mechanism which generally comprises in combination a brace or bracket adapted for attachment to the knitting machine or the like, yarn guide means on the base, a member responsive to tension in the yarn adapted to effect operation of the stop motion mechanism upon breakage of the yarn, the member being mounted on the base and having one end provided with yarn guide means, and a gravity responsive member pivotally mounted on the base having yarn guide means at its ends adjacent the guide means on the base and the first mentioned member respectively.

While the mechanism illustrated herein is 55

2

adapted to control the stoppage of the machine by electrically, pneumatically, hydraulically, or mechanically operated devices, the mechanism as shown is particularly adapted for controlling an electrical circuit and, in accomplishing this, reduces the number of electrical circuits in many breakage responsive devices by enabling a chimes under the control of a multiplicity of pair of yarn tension responsive arms to control a single circuit.

In the embodiment illustrated herein and about to be described, the foregoing is facilitated by providing a switch on the base having a pair of contact elements electrically connected to one terminal of the switch and mounting a pair of yarn responsive members side by side on the base, each provided with a portion for engaging a contact element and each electrically connected to the other terminal of the switch, whereby breakage of the yarn detected by either of the responsive members effects closing of the stop motion circuit.

The construction of the mechanism is further simplified by providing a spring for each yarn responsive member which urges the contact portion towards the contact elements and by providing common means for simultaneously adjusting both springs.

A preferred embodiment of the invention has 30 been chosen for purposes of illustration and description and is shown in the accompanying drawing, forming a part of the specification, wherein:

Fig. 1 is a top view of a device in accordance 35 with the invention wherein a pair of yarn responsive members control a single switch circuit.

Fig. 2 is a side view of the device with a portion of the switch housing broken away and one of the yarn responsive members shown in a 40 normal position during operation and the other yarn responsive member shown in circuit closing position as a result of breakage of the yarn.

Fig. 3 is a bottom view of the device shown in Figs. 1 and 2.

Fig. 4 is a staggered sectional view taken along the line 4—4 on Fig. 2.

Referring to the drawing in detail, there is shown a device generally comprising a base or bracket 10 including a switch housing 11, a pair of yarn tension responsive arms 12 pivotally mounted on the base, and slack take-up means for each arm including a guide eye 14 fixed on the base and gravity operable means 15 cooperating with the eye 14, as described hereinafter. The arms 12 are mounted in side by side rela-

tion on the base with one arm at one side of the switch housing 11 and the other arm at the other side thereof. To accomplish this, each arm is formed of relatively stiff wire and has shaft portions 16 and 17 seated in a recess formed in the side walls of the switch housing at the edge which the bracket overlies and held in the assembled relation by securing the switch housing to the bracket at 18 and 19.

Each arm 12 has a U-shaped switch engaging portion 20 between its shaft portions extending to the left of the pivot, as viewed in Fig. 4, one of the legs of this portion having a loop 21 formed therein; and each arm has a short portion 22 perpendicular to the shaft portion 16 disposed adjacent a side wall of the switch housing, a portion 24 extending outwardly from the side wall, an elongated lengthwise extending portion 25 which is slightly bendable and resilient, and an inwardly extending transverse portion 26 at the free end of the arm supporting a yarn guide eye 27.

As shown in Figs. 2 and 4, the switch housing 11 has a switch member 29 mounted therein and electrically insulated therefrom in any suitable manner. Member 29 constitutes one terminal of the switch means and is provided with a pair of electrically connected contact elements 30 each adapted to be engaged by the U-shaped portions 20 of the arms 12. The housing constitutes the other terminal of the switch means and the arms 12 are in electrical connection therewith, whereby a circuit is adapted to be established for effecting stoppage of the machine when either of the arms engages one of the contact elements 30.

The arms 12 are each urged about their pivots to cause the U-portions 20 to engage the contact elements 30 by a spring 31 having one end connected to the loop 21 of each arm and having the other end attached to a plate 32 movably mounted in the housing for simultaneously adjusting the tension of the springs. A screw member 34 is passed through one wall of the switch housing and threaded through the plate 32 for effecting adjustment thereof, which screw member has a slotted head 35 at the exterior of the housing for operating the same.

The arms 12, during normal operation of the machine, are held in a position by the yarn passing through the eye 27 to maintain the portion 20 of the arms out of engagement with the contact elements 30, but upon breakage of the yarn are moved by the spring 31 thereof into circuit closing position, as hereinbefore described.

In order to prevent the arms 12 from moving into circuit closing position in the event the yarn becomes slack due to a condition occurring during normal operation of the machine, the gravity operable means 15 are arranged to compensate for such slack. To accomplish the foregoing, the gravity operable means 15 constitutes a lever pivotally mounted between its ends at 40 on an upwardly projecting ear or lug 41 on an extension 43 of the bracket. The pivot 40 is off-set from the middle of the lever to provide the lever with a short arm 42 and a long arm 44. The short arm has a yarn guide eye 45 at the end thereof positioned adjacent the eye 27 of the arm, and the long arm 44 has yarn guide means at the end thereof in the form of a laterally extending rod or finger 46 positioned adjacent the eye 14 on the base or bracket, the eye 45 and the rod 46 being positioned between the eyes 14 and 27.

The yarn Y is threaded through the eye 14, un-

der the rod 46, through the eyes 45 and 27 (Fig. 2) and is then led to the knitting machine, whereby during normal operation, due to yarn demand, the portion 25 of the arm is held down by the tension of the yarn. Under these conditions, the short arm 42 is held down with the eye 45 substantially in registry with the eye 27 and the long arm 44 is held up with the rod 46 above the center of the eye 14.

In the event the yarn between the machine and the eye 27 becomes slack momentarily because yarn demand ceases for a particular strand in the normal and intended operation of the machine, the longer and heavier arm 44 with the rod 46 drops by gravity, so that the rod 46 presses the yarn Y against a stop element 47, shown as inclined and extending rearwardly from extension 43; while the shorter arm 42 raises to place the yarn in a zig-zag path, thereby taking up the slack. When the arms 42 and 44 are so positioned, the eye 45 is out of line with the eye 27 and the rod 46 is out of line with the eye 14 to snub the yarn and to apply a tension thereto between the rod 46 and the machine which is effective to hold the arm 12 out of circuit closing position in opposition to the influence of the spring 31.

The foregoing slack take-up function is accomplished without impairing the effectiveness of the device from detecting a break in the yarn and effecting stoppage of the machine. Should a break occur, the yarn goes completely slack and the lever 15 is ineffective to accommodate such slack, whereby the spring 31 moves the arm portion 20 into engagement with the switch contact element 30.

From the foregoing description, it will be seen that the present invention provides a new and useful stop motion device for knitting machines, which has the advantages of being simple and economical in construction, reliable in operation, and is readily adjusted. The device is readily adapted to withstand long and continuous use without impairing its reliability or requiring repair.

The device is also particularly useful in connection with machines utilizing more than one color of yarn or thread. For example, when one colored thread, such as red, is being drawn by the knitting mechanism through the device from the bobbin, the other colored thread, such as blue, is stationary under a certain amount of tension brought about by the brake mechanism of this invention, which brake mechanism constituted by the rod 46 and stop element 47 prevents the blue thread from slackening further through additional thread from the bobbin and thus prevents the arm 12 (for the blue yarn) from stopping the machine.

As various changes may be made in the form, construction and arrangement of the parts herein, without departing from the spirit and scope of the invention and without sacrificing any of its advantages, it is to be understood that all matters herein are to be interpreted as illustrative and not in any limiting sense.

What is claimed:

1. In a stop motion mechanism for knitting machines and the like, the combination of a base, yarn guide means on said base, a member responsive to tension in the yarn adapted to effect operation of the stop motion mechanism upon breakage of the yarn, said member having one end mounted on said base and having yarn guide means at its other end, and a member pivotally

mounted on said base having yarn guide means at one end adjacent said yarn guide on said base and having yarn guide means at its other end adjacent said yarn guide means on said first mentioned member.

2. In a stop motion mechanism for knitting machines and the like, the combination of a base, a yarn guide eye on said base, a member responsive to tension in the yarn adapted to effect operation of the stop motion mechanism upon breakage of the yarn, said member being mounted on said base having a free end provided with a yarn guide eye spaced from said first eye, and a lever pivotally mounted between its ends on said base between said aforementioned guide eyes, said lever having an arm provided with a yarn guide rod adjacent said eye on said base and having a second arm provided with a yarn guide eye adjacent said eye on said member.

3. In a stop motion mechanism for knitting machines and the like, the combination of a base, a yarn guide eye on said base, a member responsive to tension in the yarn adapted to effect operation of the stop motion mechanism upon breakage of the yarn, said member being mounted on said base having a free end provided with a yarn guide eye spaced from said first eye, and a lever pivotally mounted between its ends on said base between said aforementioned guide eyes, said lever having an arm provided with a yarn guide rod adjacent said eye on said base and having a second arm provided with a yarn guide eye adjacent said eye on said member, said first arm being longer than said second arm.

4. In a stop motion mechanism for knitting machines and the like, the combination of a base, switch means on said base having a contact element, a member responsive to tension in the yarn pivotally mounted on said base having yarn guide means at one end thereof and having its other end positioned to engage said element upon breakage of the yarn, yarn guide means on said base, and a second pivotally mounted member on said base having yarn guide means adjacent said guide means on said base and having yarn guide means adjacent said guide means on said first member.

5. In a stop motion mechanism for knitting machines and the like, the combination of a base, switch means on said base having a contact element, a member responsive to tension in the yarn pivotally mounted on said base having a yarn guide eye at one end thereof and having its other end positioned to engage said element upon breakage of the yarn, a yarn guide eye on said base spaced from said eye on said member, and a lever pivotally mounted between its ends on said base between said aforementioned guide eyes, said lever having an arm provided with a yarn guide rod adjacent said eye on said base and having a second arm provided with a yarn guide eye adjacent said eye on said member.

6. In a stop motion mechanism for knitting

machines and the like, the combination of a base, switch means on said base having a pair of contact elements electrically connected to one terminal of said switch means, a pair of members each responsive to tension in a strand of yarn each pivotally mounted on said base and each having yarn guide means at one end thereof and each having its other end positioned to contact one of said contact elements upon breakage of its strand of yarn, said members being electrically connected to the other terminal of said switch means, whereby said switch means is adapted to close an electrical circuit upon breakage of either said strands of yarn, and stack take-up means for each strand of yarn for preventing unintentional closing of the circuit.

7. In a stop motion mechanism for knitting machines and the like, the combination of a base, switch means on said base having a pair of electrical contact elements, a pair of members each responsive to tension in a strand of yarn pivotally mounted in side by side relation on said base and each having yarn guide means at one end thereof and each having its other end positioned to contact one of said contact elements upon breakage of its strand of yarn, a spring for each of said members having one end connected to urge said last mentioned end of said members toward its contact element, a member having the other end of said springs connected thereto and a screw interconnecting said last mentioned member and said base for adjusting the tension of said springs.

8. In a stop motion mechanism for knitting machines and the like, the combination of a base, yarn guide means on said base, a member mounted on said base responsive to tension in the yarn adapted to effect operation of the stop motion mechanism upon breakage of the yarn, said member having yarn guide means at one end thereof, and gravity operable means having yarn engaging means adjacent said guide means for preventing slack in the yarn between said yarn guide means, said gravity operable means including a lever pivotally mounted on said base with a lateral finger thereon serving to engage the yarn against the base and arrest further movement of the yarn.
